INTERNAL GRINDING MACHINE

Harry Hales Asbridge, Moss Lane, Ashton-on-Mersey, England, assignor to The Churchill Machine Tool Company Limited, Broadheath, near Altrincham, England, a British company

Application March 21, 1938, Serial No. 197,269
In Great Britain April 1, 1937

3 Claims. (Cl. 51—165)

This invention relates to internal grinding machines of the type in which the hole being ground is gauged intermittently for the purpose of controlling the grinding operation and stopping the 5 same when the hole is of correct size.

The object of the present invention is to provide improved means for controlling the gauging operation and for retracting the grinding wheel radially from the work surface when the hole is 10 ground to size.

The invention comprises the arrangement (in an internal grinding machine in which the work-piece is reciprocated over the grinding wheel) wherein the gauge is normally held away from 15 the work-piece until the grinding operation is approaching completion when it is permitted to move into and remain in a gauging position but prevented from coming into contact with the grinding wheel, the gauge when it enters the 20 workpiece causing mechanism to retract the grinding wheel radially from contact with the workpiece.

The invention further comprises the provision of electrical means operated when the feed to the 25 grinding wheel is approaching its maximum to allow the gauging means to move into and remain in the gauging position.

The invention further comprises the provision of electrical means operated when the gauge goes 30 into the ground hole in the workpiece to cause the grinding wheel to retract radially from contact with the workpiece.

Referring to the accompanying explanatory drawings:

35 Figure 1 is a part elevation and part sectional elevation of part of a grinding machine constructed and arranged in one convenient form in accordance with this invention.

Figure 2 is a plan view of the work headstock. 40 Figure 3 is a cross sectional elevation on the line 3—3 of Figure 1.

Figure 4 is a plan of Figure 3, with the grinding headstock removed and with certain parts in section.

45 The work headstock *a* has the mandrel *b* for the workcarrier *c* journalled therein. A work-piece is shown at *d*. The grinding wheel *e* is carried by the shaft *e*¹ journalled in the grinding head *f*.

50 The work gauge *g* which is to gauge the hole in the workpiece *d* is carried by the spindle *h* secured to a crosshead *i* which has sleeves *j* to ride upon bars *k* upon the workhead. One sleeve *j* has an electric contact *m* thereon which cooperates with 55 a contact *n* to close a circuit through a solenoid *o*

to be hereinafter referred to. There is a spring at *p* pressing the slide *i* in one direction and a spring at *q* pressing upon a plunger *r* secured to or integral with the armature of a solenoid indicated at *s*. 5

The table *t* carrying the workhead is reciprocated with short strokes when the workpiece is in position to be ground by the grinding wheel *e*, by the spring loaded part *u* projecting from the frame *v* fulcrumed at *w* and oscillated by the 10 connecting rod *x* from a suitable crank.

An arm *4* which can be adjusted in position by the screwed stud *5* is mounted upon the bed of the machine by a suitable bracket *y* so that it remains stationary as the table *t* reciprocates. It 15 can move to the left in Figure 2 as the workhead is withdrawn to move the workpiece completely clear of the grinding wheel after the grinding operation is completed. During the normal reciprocations of the table *t* when the grinding 20 operation is in progress, the arm *4* prevents the slide *i* moving sufficiently forward to allow the gauge *g* to come into contact with the grinding wheel *e*. 25

The table *f*¹ carrying the grinding head (see Figure 3) has a slide *6* therein from which projects the lug *7* which bears upon the cam *8* splined upon the shaft *9*. The counterbalance weight *10* holds the lug *7* against the cam *8* and therefore as the cam is turned by its shaft *9* gives the requisite feed movements to the grinding wheel. The shaft *9* is turned by gearing in the box *z* and there is a hand wheel *11* on the shaft, said hand wheel having a cam *12* thereon (see Figure 1). When the cam *8* is approaching the 30 position which gives the desired maximum amount of feed to the grinding wheel, the cam *12* thereon engages the member *13* and closes the contacts *14*, *15*, with the result that a circuit which includes the solenoids *s* is closed and the solenoid energized. The plunger *r* is then 35 withdrawn and the slide *i* can come against the stop *4*, so permitting the gauge *g* to remain in its extreme right hand position whilst the workhead is reciprocated and the workpiece *d* moved back and forth on to and off the gauge, if the gauge can enter the hole in the workpiece. When the slide *i* is permitted to move to the right in Figure 1, and the gauge can enter the workpiece, the contacts *m*, *n* close and the solenoid *o* is energized. 40

This results in the armature *16* being moved to the left in Figure 4 and turning the lever *17* about its fulcrum *18*. The part *19* of the lever *17* which comes between the collars *20* on the rod *21* coupled to the slide *6* then causes 45 50 55

such slide to be moved in the direction of the arrow 22 in Figure 4. The slot 23 in the table ¹ in which the slide 6 moves is at an angle to the direction of movement of the table and movement of the slide in the direction of the arrow 22, causes the lug 7 to slide down the incline of the cam 8 under the pressure of the weight 19, so retracting the grinding wheel radially from the face of the workpiece. It will be understood that this occurs when the workpiece is ground to size and the gauge *g* can enter therein.

The operation of the mechanism is as follows:

During the normal grinding operation, the workhead is reciprocated by the mechanism *u*, *v*, *w*, *x* and the workpiece is carried with it. The gauge *g* also reciprocates with the head, the stop 4 preventing any movement which might cause the gauge to make contact with the grinding wheel *e*. When the feed movement of the grinding wheel is approaching completion by the turning of the cam 8, contacts 14 and 15 are closed by the cam 12 on the hand wheel 11 and the solenoid *s* is energized to withdraw the plunger *r* from the slide *i*. The latter now bears against the stop 4 under the pressure of the spring *p* so that at each reciprocation of the workhead, the workpiece will be brought against the gauge *g*. If the gauge can enter the ground hole in the workpiece, the contact *m* will move against the contact *n* and the solenoid *o* will be energized which will result in the slide 6 being moved and the grinding wheel quickly retracted radially from contact with the workpiece.

35 The feed control mechanism is similar to that described in my prior patent specification No. 2,005,332, which also describes the means for reciprocating the worktable.

What I claim is:

40 1. In an internal grinding machine of the type specified, a grinding head, a workhead, with means for its reciprocation, a workholder upon a mandrel journaled in the workhead, a gauge supported in the workholder adjacent the workpiece, a rod extending through the mandrel supporting the gauge, a slide mounted upon said

rod, an adjustable non-moving part limiting the movement of the slide towards the grinding head, a spring pressing the slide towards the said non-moving part, a solenoid controlled spring loaded part pressing the slide in the opposite direction, 5 an electric contact on the slide and a co-operating contact on the slide support, feed mechanism for the grinding wheel head, means upon said mechanism for closing the circuit through said solenoid when the feed movement is approaching 10 completion, and solenoid operated means for moving the grinding head to retract the grinding wheel radially from contact with the workpiece when the contacts upon the slide and the slide support engage.

2. In an internal grinding machine as claimed in claim 1, a rotary cam for feeding the grinding wheel head towards the surface being ground, a slide movable in the grinding head table having a lug thereon engaging said cam, a weight 20 holding the lug against the cam, and a solenoid for moving said slide in said slot to vary the position of the lug upon the cam to retract the grinding wheel radially from contact with the workpiece.

25 3. An internal grinding machine comprising a revoluble grinding wheel, a revoluble workpiece holder, means to produce relative movement between said workpiece holder and grinding wheel to bring a workpiece in the said holder over said grinding wheel, means thereafter to impart short axial vibratory movements to said workpiece holder, a gauge mounted in said workpiece holder, a spring constraining said gauge to move coaxially with and towards the workpiece, mechanical means to prevent said gauge entering the bore of the workpiece during movement of vibration of the workpiece holder towards said grinding wheel, electrically controlled means to prevent said gauge entering the bore of the workpiece during movement of vibration of the workpiece away from said grinding wheel and a switch arranged for actuation when grinding is nearly completed to put said electrical means out of action.
